UNITED STATES PATENT OFFICE

2,558,825

DOOR FASTENER FOR HINGED DOORS

George E. Dath, Mokena, Ill., assignor to W. H. Miner, Inc., Chicago, Ill., a corporation of Delaware

Application March 1, 1947, Serial No. 731,856

3 Claims. (Cl. 20—21)

1

This invention relates to improvements in fasteners of the rotary bar type for hinged doors.

One object of the invention is to provide a lever operated rotary bar fastener for a pair of hinged doors, wherein the rotary bar is mounted on one of the doors and has means thereon cooperating with fixed keepers for forcing the door, which carries the bar, to closed position and the bar has direct engagement with the other door of said pair to force the last named door to closed position.

Other objects of the invention will more clearly appear from the description and claims herein-after following.

In the accompanying drawings forming a part of this specification, Figure 1 is a broken rear elevational view of the body portion of an automobile truck provided with a pair of hinged doors, illustrating my improvements in connection therewith. Figure 2 is a broken vertical sectional view, corresponding substantially to the line 2—2 of Figure 3, said view being on a slightly reduced scale. Figure 3 is a top plan view of the pair of doors shown in Figure 1, taken at the inner end portions of said doors, said view being on an enlarged scale. Figure 4 is a horizontal sectional view, on an enlarged scale, corresponding substantially to the line 4—4 of Figure 2. Figure 5 is a horizontal sectional view, on an enlarged scale, of the inner end portion of the right hand door shown in Figure 1, corresponding substantially to the line 5—5 of Figure 2. Figure 6 is a vertical sectional view, on an enlarged scale, through the mid portion of the upper end of the rotary operating bar of my improved mechanism. Figure 7 is a plan view, on an enlarged scale, of the lower keeper of my improved mechanism, illustrating the operation of the keeper engaging means, showing the same in three different positions, one of said positions being shown in full lines and the remaining two being shown in dotted lines.

In said drawings, 10 indicates the rear end wall of the body of an automobile truck. The wall 10 is provided with the usual opening 11, closed by a pair of hinged doors 12 and 13, supported along their outer edges by hinges 14—14. The doors 12 and 13 are of a well-known type employed on automobile trucks, each door having front and rear spaced walls 15 and 16.

In carrying out my improvements, I provide the door 12 with a vertically disposed Z-bar 17 at its inner edge, the web 18 of which forms the vertical end wall of said door structure. The rear flange 19 of the Z-bar 17 extends inwardly of the

2

door and is fixed to the inner side of the rear wall 16. The front flange of the Z-bar, which flange is indicated by 20, projects laterally outwardly from the web 18 thereof and extends along the inner side of the front wall 15 of said door and is secured to said wall in any suitable manner.

The door 13 is also provided with a vertically disposed Z-bar 21 at its inner edge, the web 22 of which forms the vertical end wall of said door. The rear flange 23 of the Z-bar 21 projects laterally outwardly from the web 22 and is fixed to the inner side of the rear wall 16 of the door 13. The front flange 24 of the Z-bar 21 projects inwardly along the front wall 15 of the door 13 and is fixed to the inner side of said wall.

As will be seen upon reference to Figures 3 and 4, when the doors are in closed position, the flange 20 of the door 12 overhangs the flange 23 of the door 13. As shown in said figures, the front wall 15 of the door 12 is preferably extended outwardly beyond the vertical end edge of the flange 20 of the Z-bar 17 to overlap the inner edge portion of the door 13 when the doors are closed.

25 My improved fastener is carried by the door 12, and the front wall 15 of said door is provided with an inwardly offset section 25 between the top and bottom portions of said door, adjacent the inner edge thereof, forming a laterally elongated pocket 26, adapted to receive the operating handle lever of my improved door fastener when the bar and the handle lever thereof are in position to hold the door closed. The door 13 is provided with a vertically extending, outwardly facing rubber strip 27 along its inner edge portion, the strip 27 being mounted on the front side of the flange 23 of said door. The rubber strip 27 is preferably covered by a canvas strip 28 which overlaps the same.

40 My improved door fastener means proper comprises broadly an operating bar A, keeper engaging end members B—B at opposite ends of the bar, an operating handle lever C for said bar, top and bottom keepers D—D with which the end members B—B cooperate, and bearing brackets E—E for the bar A.

The operating bar A is in the form of an elongated tube of circular cross section, mounted on the door 12 at the inner side of the flange 20 of said door. The bar A extends vertically and carries the keeper engaging end members B—B at the top and bottom ends thereof.

Each keeper engaging end member B is in the form of a cylindrical cap providing a socket 29 within which the corresponding end of the bar A

is telescoped. At the outer end, each end member B is provided with a projecting eccentric crank pin 30, adapted to cooperate with the corresponding keeper. The two end members B—B are fixed to the bar A by being welded thereto, as indicated at 31. The keeper engaging end members B—B at the top and bottom ends of the bar A serve as bearing elements of said bar, said end members being rotatably supported within the bearing brackets E—E, which are secured to the inner side of the flange 20 of the door 12, adjacent the top and bottom edges of said door. To hold the bar A against endwise displacement, each end member B is provided with an annular stop collar at its inner end in the form of an annular outstanding flange 32, the flange 32 of the bottom end member being supported on the lower bearing bracket E and that of the top end member being engaged with the underneath side of the top bearing bracket E. The bearing brackets E—E are of the common two-part construction, comprising front and rear sections 33 and 34, embracing the corresponding bearing portion of the bar A.

The operating lever C for rotating the bar A is fixed to the latter, being preferably welded thereto. The lever C is located so that it swings into the pocket 26 when the doors are forced to closed position, the side wall 35 of the pocket and the Z-bar 17 being slotted, as indicated at 36, to accommodate the handle lever in its swinging movement. The usual latch, indicated by 37, is also provided on the door 12 for locking the lever C in position when the doors are closed.

The keepers D—D are of well-known design, each keeper being in the form of a block provided with an inclined cam slot 38 with which the crank pin 30 of the corresponding end member B is engageable. The keepers D—D are mounted within the door opening 11, above and below the door 12, in proper position to be engaged by the crank pins 30—30 of the top and bottom end members B—B.

The operation of my improved door fastener is as follows: In closing the doors 12 and 13, the door 13 is first swung to partly closed position. Then the door 12 is swung partly closed to bring the crank pins 30—30 of the operating bar into cooperative relation with the keepers B—B, as shown in full lines in Figure 7. The bar A is then rotated in contraclockwise direction, as viewed in Figure 7, engaging the crank pins within the slots 38—38 of the keepers and camming the door shut. The relative positions of the crank pin 30 of the lower keeper engaging end member in the slot 38 of the keeper, as it enters the slot and cams the door closed, are shown by the two dotted line positions in Figure 7. As the door 12 is cammed inwardly, the bar A engages the projecting strip 27 of the door 13 to force the latter tightly closed. When the doors have been forced home to closed position, the handle lever C is locked in position by the latch 37 to maintain the doors closed.

In opening the doors, the door 12 is cammed outwardly by rotation of the bar A. After it has been thus forced partly open, it is manually swung to completely open position by the attendant, thus leaving the door 13 free to be swung open also.

I claim:

1. In a fastener for a pair of doors hinged along their outer edges for swinging movement to closed position with the inner edge portion of one door overlapping the inner edge portion of the other door, the combination with an elongated, vertically disposed, rotatable operating bar for forcing said doors closed, mounted on the inner side of the door which has the inner edge overlapping the other door when closed; of a strip of resilient material secured to the outer side of the inner edge portion of said last named door tightly engaged by the length of said bar when the doors are forced closed by said bar.
2. In a door construction, the combination with a door hinged along its vertical outer edge, said door having a lengthwise extending projecting flange along its inner edge; of a second door hinged along its vertical outer edge, said door having a lengthwise extending projecting flange along its inner edge underlying the flange of said first named door when the doors are closed; a vertically disposed, elongated, rotary operating bar for forcing said doors closed, mounted on the inner side of the flange of said first named door, said bar being journaled in bearing brackets fixed to the inner side of the flange of said first named door; and a vertically extending, elongated strip of resilient material fixed to the outer side of the flange of said second named door, said strip being engaged directly by said bar when the doors are closed.
3. In a door fastener mechanism for a pair of doors hinged at their outer edges and having the inner edge of one of the doors of said pair overlying the inner edge of the other door of said pair when the doors are closed, the combination with a vertically disposed, elongated, rotary operating bar for forcing said doors closed, rotatably supported on the inner side of the door which has its inner edge overlying the inner edge of the other door when said doors are closed, said bar being engageable with the outer side of said other door to hold the same closed when said bar is operated to force said doors closed.

GEORGE E. DATH.
